UNITED STATES PATENT OFFICE.

DAVID P. PAGE, OF GRAND RAPIDS, MICHIGAN, ASSIGNOR TO GRAND RAPIDS BRUSH COMPANY, OF GRAND RAPIDS, MICHIGAN, A CORPORATION.

BRUSH-MACHINE.

1,014,973.

Specification of Letters Patent. Patented Jan. 16, 1912.

Application filed December 5, 1904. Serial No. 235,564.

To all whom it may concern:

Be it known that I, DAVID P. PAGE, a citizen of the United States, residing at Grand Rapids, in the county of Kent and State of Michigan, have invented new and useful improvements in Brush-Machines, of which the following is a specification.

My invention relates to brush machines and more particularly to the means for forming the staple or fastening device which attaches the tuft of bristles to the wood or block, and for conveying such device to the setting jaws and for setting same, also to the means for separating and forming the tuft of bristles, also to the means for adjusting or centering the brush back or block so that the tuft of bristles will be attached in exactly the proper place, and my object is to provide the same with various new and useful improvements hereinafter more fully described and particularly pointed out in the claims, reference being had to the accompanying drawings, in which:

Figure 1 is a side elevation of a machine embodying my invention; Fig. 2 is a front elevation of the same with a portion of the casing broken away showing the cam disk 48; Fig. 3 is a section on the line 3—3 Fig. 1 showing reverse side of cam disk 48 and other details; Fig. 4 is a detail partly in side view and partly in cross section of the mechanism for separating the bristles into tufts and for conveying the tufts to the setting jaws; Fig. 5 is an enlarged perspective of the bristle fastening device. Owing to the peculiar method in which this fastening device operates to retain itself and the tuft of bristles, I prefer to call it an anchor rather than to use the more general term staple. Figs. 6, 7, and 8 are enlarged detail views showing portions of anchor cutting and conveying mechanism; Fig. 9 is a cross section of the block centering mechanism; Fig. 10 is an enlarged longitudinal section of the tuft setting and anchor driving device; Fig. 11 is a section of the same on the line 11—11 of Fig. 10; Fig. 12 is a section of the brush back showing one tuft in position and another tuft in the jaws about to be set in the hole; Fig. 13 is another section of the brush back showing a tuft in position and a side view of the anchor. Fig. 14 is a detailed sectional view through the driving pulleys and cam disk operative therewith. Fig. 15 is a detailed face view of the cam plate 42.

2 represents the main frame of the machine; 3 the main driving shaft, which shaft is carried in journal boxes on the frame, such journal boxes being shown at 4 and 5.

8 is a pulley carrying the driving belt and mounted on a sleeve upon the shaft 3. 9 is a tapering pulley rigidly attached to the shaft 3. 10 and 11 show lever arms so pivoted as to bring about an endwise movement of this sleeve upon the shaft 3 and thereby carry the pulley 8 to or from the tapered pulley 9. The movement of the pulley 8, by the arm 10, is clearly shown in sectional detail in Fig. 14. The pulley 8 is rotatable and also slideable upon the shaft 3. 60 A sleeve 8^a shouldered at one end, is also slideable upon the shaft 3, and is held to the pulley 8 by a collar 8^b. This sleeve 8^a is kept from rotating by its connection with the arm 10. This arrangement of parts constitutes a friction clutch by which motion may be imparted to the shaft 3 at the pleasure of the operator. 75

12 is a cam disk attached to the shaft 3 and having in its face a cam groove 12' of 80 suitable shape, in which travels the roller on the end of the crank arm 13. This crank arm is rigidly attached to the rock shaft 14, and the shape of the cam groove is such as to convey to the said shaft an oscillatory rotating motion through only a part, approximately one-fourth of a revolution. The other end of this shaft 14 carries the eccentric 15, and thus a reciprocating vertical motion, but through only a short stroke, is 85 given to the connecting rod 16. These parts 15 and 16 are shown in end view in Fig. 2.

17 is a vertically-sliding block attached to the rod 16 by the screw 18, by which the rod thus imparts vertical motion to the block. 95

19 and 20 are guides upon the frame, so adjusted as to insure a proper vertical sliding motion to the block 17. This block 17 carries, projecting downward therefrom, the staple or anchor former 22, and the holder therefor, 21.

23 and 25 are the dies upon the upper surface of which rests the stock from which the anchor is formed, and through which the former 22 passes, punching out and 105 carrying down the anchor or staples. The die 25 is adjustable by means of the screw 31 to insure proper spacing apart of the dies.

The stock from which the anchor is con- 110

structed is a flat wire shown in Fig. 2 at 108. This passes down between feed rollers 35 and 36. The lower roller 36 is journaled in a projection 38 of the frame of the machine and the upper roller 35 is carried by a bearing 37 vertically movable on the post 39. This post 39 has a screw threaded connection with the projection 38 and is provided at its upper end by a head 40, and a 10 spring 41 intervenes between such head and a movable bearing 37. It is evident that by screwing down the post 39 that the pressure on the spring 41 can be increased and thereby the grip of the rollers upon the wire can 15 be regulated. These feed rollers can be actuated in any suitable manner.

The plate 27, Figs. 6, 7, and 8, is rigidly attached to one end of a short rock shaft 27^a. The upper edge of this plate is upon the arc 20 of a circle struck from the center of the said shaft. The lower edges of the dies 23 and 25 are upon the arc of a circle concentric and slightly larger.

A dasher or carrier 26 is rigidly attached to the plate 27. The upper edge of this dasher is upon the arc of the same circle as the edge of the plate 27. The main body of the dasher lies close against the plate, but a part of the dasher near one end and 30 adjacent to the plate is cut away as shown in Fig. 7. The upper surface of the dasher 26 and the plate 27 taken together thus form a smooth curved surface through most of their arc, but have a slightly raised portion 35 near one end as shown in Figs. 6 and 8. This raised portion lies close to the lower edges of the dies 23 and 25 and contains a recess 26^a as shown in Fig. 7 suitable for receiving the anchor which has been stamped 40 from the wire 108 by the anchor former 22.

To the dasher 26 and plate 27 by means of a suitable pivot, I attach a link 28, which at its other end is suitably pivoted to the bar 29. This bar 29 at one end is pivoted 45 to any suitable part of the frame and at the other end carries the anchor-supporter 29^a. This supporter is kept in proper position by the spring 30, Fig. 6, which at one end bears against the said supporter, 50 and at the other end is attached in any suitable place on the bar 29.

When an anchor is formed by the anchor forming mechanism, it is delivered into the recess 26^a. The mechanism is so timed that 55 at this point that dasher 26 and plate 27 will be rotated, carrying the anchor beneath the lower edge of the die 23 to the lower end of such die. The link 28 and the bar 29 are so pivoted and connected that at the same moment the supporter 29^a will be lifted and will support the anchor against dropping down any farther as shown in Fig. 8.

32 is a finger bar, preferably of thin flat steel, and developed into the carrying fingers 60 112 and 113. This bar 32 is in turn carried

by the slide 42 and longitudinally adjustable thereon by means of the slotted holes 33 and 34 and attaching screws passing therethrough. This slide 42 with the bar 32 carried thereby, is intended to have a reciprocating longitudinal motion, and operates in any suitable guides or ways 42^a upon the frame. It is actuated and given its reciprocating motion by the actuating mechanism through the connection 124, as herein-after described.

The finger bar 32 is divided as shown in Figs. 6 and 8 into two fingers, 112 and 113, which evidently will be by the spring of the material held together, but which will be 80 capable of slight separation as the contingencies of operation may require. The finger 113, which is the lower one, I have shown longer than the finger 112. At the moment when this finger bar is carried forward to the point where the staple or anchor is held by the supporter 29^a, the die 23, the dasher 26, and plate 27, this lower projecting finger will pass between the lower projections 114 of the anchor and the middle portion 118 of the anchor will either lie against the end of the arm 112, the anchor thereby hanging in a vertical position, or said middle portion 118 of the anchor will pass between the fingers 112 and 113 and be 90 held in a spring grip. The space 26^b between the dasher 26 and plate 27 permits the fingers thus to pass therebetween. By this means the fingers can take the anchor from the position in which it is thus held 100 and carry it laterally until it is gripped by the setting jaws, as hereinafter described.

At a point near its end the main shaft 3 carries the cam 43, the position of which is shown in Fig. 1, and the shape of which is 105 shown in Fig. 3. Upon one side of this cam is located the arm 45 carrying the roller 44. This arm 45 is connected at its upper end by the spring 47 to an opposite arm 121, and this spring connection permits the arm 45 to be actuated by the revolution of the cam 43. The arm 45 at its other end is pivoted to the frame at 46. This arm 45, through suitable connections 125, 126, and 128 rocks the shaft 27^a and thus actuates 110 the anchor-conveying and holding mechanism. The opposite arm 121 carrying the roller 120, also in contact with and operated by cam 43, is pivoted to the main frame at 122, and at its other end is connected by the rod 124 to the finger carrying slide 42 giving the same the proper reciprocal, longitudinal motion. It is thus evident that the cam 43 actuates all of the anchor-conveying mechanism.

Near its extremity the shaft 3 carries the cam disk 48, shown in Figs. 2 and 3 and contained in the casing 48^a which is a part of the framework. Upon the face side of this cam disk 48 are cam grooves 67 and 68 125

Fig. 2. In these cam grooves travel respectively the rollers 67^a and 68^a shown in Fig. 10. 64 is a removable cap for the casing forming the guide or way 63 for the driving mechanism. 65 is a vertically reciprocating slide operated within the casing 64 and actuated by the roller 67^a in the groove 67. 66 is another vertically reciprocating slide or frame moving within the slide 65 and actuated through a slot 65^a in said slide 65 by the roller 68^a in the groove 68. The lower end of this slide 66 carries the jaws 73 and 74 through the pivotal connections 75 and 76. Within the slide 66 is situated a driver head 69 which is shouldered at 69^a and which carries a downwardly projecting driver which is narrowed and beveled at 71 and which carries at its lower end the immediate driver or punch 72. This driver head 69 reciprocates within the slide 66 and is fastened to the slide 65 by the studs 70 and is thus actuated by the roller 67^a. The cam grooves 67 and 68 are of such shape and size that, at the proper time in the operation 25 of the device, the slide 65 and the attached driver head 69 are carried down a short distance from the position shown in Fig. 10. Thereupon the bevel 71 acting as a cam, opens the upper end of the jaws and closes the lower end of the jaws causing these 30 lower ends to grip the anchor which has been presented by the carrying fingers and the tuft of bristles which has been presented by the mechanism designed for that purpose. Thereupon, these cam grooves in their further action, cause both slides, represented by 35 65 and 66, to be carried downward so that the jaws present the tuft and anchor at the top of the hole in the brush block. Thereupon, the slide 65 and the attached driver head 69 are given further downward motion. The upper ends of the jaws come in contact with the shoulders 69^a and thereby, 40 with said further downward motion, the anchor or staple is driven into the wood and the tuft is firmly attached. In this operation the lower end of the punch 72 rests upon and drives the anchor, and the cam grooves may be so adjusted that this punch 45 will come down and rest upon the anchor at any desired point in the operation. Upon the other side of the cam disk 48 is found the cam groove 50 shown in Fig. 3. In this groove travels the roller 50^a, shown in operative position in Fig. 9. This cam groove is circular during most of its course, but has two curves toward the center, indicated by 51 and 52. The roller is connected with the vertically-sliding block 49, which moves 50 within a portion of the main frame shown by 2^a. It is evident, therefore, that at two different points in the revolution of the cam disk 48, this sliding block 49 will be lifted periodically above its normal position. This 55 sliding block 49 carries, pivoted thereto, the

lever arm 51, the point of pivotal attachment being represented by 56.

57, 58, and 59 represent means for exerting a downward spring tension upon the upper end of lever arm 51 and outside of the 70 point of attachment 56, whereby this lever arm is kept normally in contact with the anti-frictional roller 60 carried by the part 2^a of the frame to guide the arm 51 suitably attached to the frame. In other words the part 57 is slidable within the sliding block 49, the lower end of which is forced against the upper end of the lever arm 51 and outside of its pivotal connection 56 by means of a spring 58. The upper end of the spring 80 rests against a retaining plate 59 which is attached to the sliding block 49.

52 is an extension of arm 51 carrying the vertical cylindrical guide 53, and in this is the centering pin 54 preferably brought to 85 a point in the bottom and rising and falling in the guide 53 under the pressure produced by the spring 55 (see Fig. 2).

128^a is a guiding surface on the frame and provided with a straight vertical face. With this face the arm 51, or a suitable projection thereof, makes contact, and thereby, when in the downward motion of arm 51, this projection strikes this face or guide, the remaining motion of arm 51 and of the 90 centering pin 54 will be vertical. Normally the face 128^a presents an unbroken surface to the projection of the arm 51, making contact therewith, but a portion of this face represented by 124^a, Fig. 3, is made in the 95 form of a slide to slide horizontally in the body of face 128^a and provided with means for withdrawing the same a short distance, so that when it is withdrawn a notch or recess is produced in this guide face 128^a. This 100 portion of the guide 128^a may be actuated in any suitable manner, preferably by an arm 124^b engaged by the lever 121.

As the sliding block 49 is carried down after a momentary lifting, the projection on 110 51 will come in contact with the surface 128^a, and the centering pin 54 will be carried in a directly vertical path downwardly. The parts are so attached to the frame that at this time the position of the centering pin, viz., the position shown in Fig. 9 will be precisely in the path which will later be taken by the descending setting jaws, and will specify the exact spot which will be reached by the punch and into which the anchor will be drawn. The operator handling the brush block 116 supported on the table 117 will adjust the block so that the bored hole will be, according to his eye, in the proper position. The centering pin will then descend into the hole and correct any imperfection in the placing made by the operator, moving the block to its exactly proper position. The beveled or pointed 115 lower end of the centering pin assisting in 120 125 130

this placing operation. As the setting jaws begin to descend to drive the anchor to position, the arm 51 will be slightly raised and the sliding stop 124^a will be withdrawn. 5 The spring tension will then throw the projection on the arm 51 into this recess in 128^a and the centering pin will take the position shown in Fig. 1 out of the way of the descending setting jaws. Then, simultaneously with the raising of the setting jaws, 10 the arm 51 will be further lifted and the centering pin will take a position considerably above and to the left of that shown in Fig. 9, and will then be ready for the reverse stroke. The length of time during 15 which the centering device will maintain each position and during which it will be in motion, will be determined by the shape of the cam groove 50 and these timing arrangements will be modified as the operation requires. 20

The jaw 74 is provided with a notch 77 adapted to receive and assist in holding a tuft of bristles in proper position when the 25 jaw 73 is closed thereupon.

The bristle and tuft separating and conveying mechanism is shown in Fig. 1 and parts of it in detail in Fig. 4. Fig. 1 shows the parts in position taking a tuft of bristles 30 just conveyed from the hopper and Fig. 4 shows the same parts at the point of delivering the tuft of bristles to the setting jaws. The arm 78 pivoted to the main frame at 79 carries a pin or roller which travels in the 35 cam groove on the hub 6. The arm is thereby given a swing or pendulum motion. At its lower end it is pivoted to the bar 80 and this bar in turn is supported by the arm 82 which is pivoted to the bar at 81 and the 40 main frame at any desired point. This arm 82 gives direction to the forward end of the bar 80. This forward end carries the bristle jaws 83 and 84. One of these (84) is rigidly attached to the bar, and the other is 45 pivoted at 108^a. To the pivoted jaw 83 is connected the rod 101, which rod is in turn attached to the arm 100, and this arm 100 is attached to the pivot, connecting the arm 78 and bar 80. The attachment of the arm 50 100 to this pivot is free, and a spring 102 is provided, the pressure of which normally holds the bristle jaws closed as they are shown to be in Fig. 4. 98 and 99 are two trips attached to the frame or hopper at 55 proper positions so that in the reciprocating motion of the arm 80 these trips will successively engage with the arm 100, and will momentarily trip the jaws open. The arm 100 passes over the point of trip 99 at the 60 extreme limit of its forward stroke and just at the point where the stroke is reversed, the jaws are held open momentarily. Trip 98 makes contact with the arm 100 at the extreme limit of the backward stroke, and the 65 jaws are therefore held open only momen-

tarily at this point. This operation enables the jaws to open and close upon, and grasp the tuft of bristles presented at the point shown in Fig. 1 and the trip 99 acts upon the arm 100 allowing the jaws to open and release this grasp upon the tuft of bristles and leave the same in the setting jaws at the point shown in Fig. 4. 110 and 111 are the upper and lower walls of the bristle hopper. The series of bristles which lie cross-wise of the hopper and are, therefore, indicated in the drawing in cross-section, are shown by 92. The follower 93, impelled by the cord 94, passes over the pulleys 95, and the weight 129 constantly presses the bristles toward the tuft-separating mechanism. An arm 103 is pivoted to the main frame, as shown in Fig. 1, and is operated by a roller traveling in the cam groove in the hub 7 and through the link 104, rocks the bell crank 85 lever 105, which is pivoted to the hopper at 106, and has its horizontal arm 86 carrying a separator head 87. This separator head is a comparatively thin piece of metal formed upon an arc of a circle of which the pivot 106 is the center. Near one end of this separator head 87 is a notch 88 of proper size and shape to accommodate a tuft of bristles. The depth of said notch may be varied by means of a thumb screw 89 thus regulating the size of the tuft of bristles to be separated from the series 92 in the hopper. This separator head is provided with suitable guide-ways of which 85 is a part.

The rocking of the shaft 106 causes the 100 arm 86 and the separator head 87 to rise, the head 87 carrying with it in the notch 88 a portion of bristles of suitable size for a tuft to be inserted in the brush block. This tuft is raised until it is under the movable bristle jaw 83. At this moment the bar 80, carrying the bristle jaws 83 and 84 and actuated by the arm 78, moves forward a short distance releasing the arm 100 from the trip 98 and allowing the movable jaw 83 to 110 swing down pressing the tuft of bristles from the slot 88 and gripping such tuft between jaws 83 and 84. The separator head is then caused, by rocking of shaft 106, to be lowered out of the way of jaws 83 and 84 after which the bar 80 is caused to have further forward movement and to deliver the tuft of bristles beneath the setting jaws 73 and 74 which then descend, as shown in Fig. 4, and grip them. The bar 80 moving backward on the return stroke causes the arm 100 to engage the trip 99 thus opening the jaws 83 and 84 allowing them to release their grip on the tuft which is now held by the jaws 73 and 74 and is ready to be set, 115 together with the anchor, in the brush block.

The form of anchor shown in Fig. 5 is the one which is preferably used, this being an enlarged view. The operation of this anchor is shown clearly in Figs. 12 and 13. 120

The lower projections of the anchor 114 straddle the tuft at its center portion as shown in Fig. 12, said tuft is folded up past the middle portion 118 of said anchor and the lower projections 114 are driven a short distance into the wood at the bottom of the hole. The upper projections 115 are spread so as to enter the wood at the sides of the hole and thus prevent the anchor from being withdrawn.

The operation of these parts has been stated in connection with the description thereof. To summarize the same it is clearly apparent that the bristles are placed in the hopper and the suitably bored brush block is manually controlled by the operator upon the table provided therefor. A tuft of bristles is then separated out of the mass in the hopper by the tuft-separating mechanism, and carried by the separator head 87 to the bristle jaws 83 and 84. It is seized by these jaws and carried to the setting jaws 73 and 74. At the same time the anchor is formed by the anchor-forming mechanism and carried by the conveyer and finger bar and delivered to the setting jaws. At about the same time the centering device, carrying the centering pin, descends and the pin enters the hole in which the tuft of bristles is to be inserted and adjusts that hole and the block in which it is bored to the exactly proper position. The centering device then rises and is removed from the descending path of the setting jaws which carry the tuft of bristles down into the hole. The anchor which has been carried also by the setting jaws and in a position above the bristle tuft, is then driven down by the punch and the tuft of bristles, indicated by 92^a in Fig. 12, doubles up, as shown, around the driver and anchor, and upon the withdrawal of the driver, forms the ordinary complete tuft of bristles permanently attached to the brush block.

I claim—

1. In a brush machine, a frame, an anchor material feeding means, means for forming anchors of said material, means for moving the anchors made by said forming means, away from the latter, means for limiting the movement of said anchor moving means, a combined anchor and tuft setting mechanism, means for gripping the anchor and delivering it from said limiting means to said combined anchor and tuft setting mechanism, a block to receive the tufts and anchors, means for centering the block, a receptacle for the bristles, means for removing tufts of the bristles from said receptacle,

means for delivering the bristles from said removing means to said combined anchor and tuft setting mechanism, and means for operating the setting mechanism after it has received an anchor and tuft to secure the tuft in said block.

2. In a brush machine, a frame, an anchor material feeding means, means operating upon said material to form anchors, a combined anchor and tuft setting mechanism, means for delivering the anchors successively to said combined anchor and tuft setting mechanism, a block to receive the tufts and anchors, a receptacle for the bristles having an open inner end, means within the receptacle to feed the tufts gradually toward the open inner end of said receptacle, an arcuate head provided with a notch to receive bristles from said receptacle, means for raising and lowering said head to remove tufts of bristles from the receptacle by its upward movement, means constructed and arranged to remove the tuft from the notch of said head while the latter is at one limit of its movement and deliver the tufts successively to the combined anchor and tuft setting mechanism, means for operating the combined anchor and tuft setting mechanism after it has received an anchor and a tuft to effect a securing of the tufts and anchors in said block, and means operable to accurately position the block to receive the tufts and anchors.

3. In a brush machine, a frame, anchors, means for moving the anchors from one part of the frame to another part thereof, means for limiting the movement of the anchor moving means, a combined anchor and tuft setting mechanism, means for gripping the anchors one at a time and delivering them one at a time from said limiting means to said combined anchor and tuft setting mechanism, a block to receive the tufts and anchors, a receptacle for the bristles, means for removing tufts of bristles from said receptacle, means for delivering the bristles from said removing means to said combined anchor and tuft setting mechanism, and means for operating the setting mechanism after it has received an anchor and tuft to secure the tuft in said block.

In testimony whereof I have hereunto set my hand in presence of two subscribing witnesses.

DAVID P. PAGE.
